D.-C. TO A.-C. SIGNAL CONVERTER WITH
VARIABLE FREQUENCY OUTPUT
William A. Geyer, Takoma Park, Md., assignor to the
United States of America as represented by the Secretary
of the Navy
15 Filed Nov. 8, 1963, Ser. No. 322,558
15 Claims. (Cl. 331—52)

(Granted under Title 35, U.S. Code (1952), sec. 266)

The invention described herein may be manufactured and used by or for the Government of the United States of America for governmental purposes without the payment of any royalties thereon or therefor.

This invention relates generally to a magnetic-coupled multivibrator and more particularly to a magnetic multivibrator in which the frequency is determined by a saturable reactor in this circuit.

In prior art systems as, for example, in the patent to R. W. Rochelle et al, and Roland L. Van Allen, U.S. Patent No. 2,894,250, frequency of the output voltage is proportional to the direct current input information signal. In this type of device a toroidal core having an auxiliary aperture is used, on which two windings are placed. This type of device requires a special core construction in which an additional aperture in a core is needed. The two windings are wound through this aperture. Such a relatively small aperture or core window imposes stringent limitations upon the winding arrangement, that is, very thin wire must be used to get a sufficient number of turns for the magnetization of the core. This also means that the copper resistance of such a winding is necessarily high, increasing the copper losses of the circuit. In the present invention the need for such an unusual core design with an additional aperture is eliminated by replacing this core with two conventional toroidal cores. With this arrangement no special apertures are needed, thus reducing the manufacturing requirements considerably. Further, the windings on these cores may have greater number of turns as the windings may be disposed throughout the toroid core.

An object of this invention is to provide an improved D.-C. to A.-C. conversion system in which the output voltage has a frequency proportional to the magnitude of the applied variable direct control current.

Another object of this invention is to provide an improved D.-C. to A.-C. converter in which ordinary toroidal cores are employed in a saturable reactor circuit.

A further object of this invention is to provide a saturable reactor circuit for determining the output frequency of a simplified switching transistor magnetic core multivibrator in which ordinary toroidal cores are employed in said saturable reactor circuit.

A still further object of this invention is to provide a simplified magnetic coupled multivibrator with a saturable reactor circuit comprising a pair of ordinary toroidal cores.

Other objects and many of the attendant advantages of this invention will be readily appreciated as the same becomes better understood by reference to the following detailed description when considered with the accompanying drawings wherein:

FIG. 1 of the drawings illustrates a preferred embodiment of this invention in which a pair of toroidal cores are employed in a saturable reactor circuit in the output of a magnetic core multivibrator.

FIG. 2 of the drawings illustrates in graphic form the relationship between a D.-C. control voltage and the A.-C. output frequency of a magnetic core multivibrator; and

FIG. 3 of the drawings illustrates a differential type magnetic multivibrator.

Referring now to FIG. 1 of the drawings, a D.-C. to A.-C. signal converter is shown having two saturable reactors in the output circuit of a transistor magnetic coupled multivibrator. Saturable reactors SR₁ and SR₂ having windings N₁ and N₂ are connected to the output circuit of the multivibrator. The multivibrator is comprised of two switching transistors Q₁ and Q₂. The base of transistor Q₁ is connected to the collector terminal of transistor Q₂ through resistor R₁. The base of transistor Q₂ is connected to the collector terminal of transistor Q₁ through resistor R₂. The emitter terminals of transistors Q₁ and Q₂ are connected together. Saturable reactor SR₁ is provided with saturable core 11, load winding N₁ and control winding C₁. Saturable reactor SR₂ is provided with saturable core 13, load winding N₂ and control winding C₂. Load windings N₁ and N₂ of saturable reactors SR₁ and SR₂ are serially connected to output terminals 15 and 17 of the multivibrator. Load 19 is also connected to output terminals 15 and 17. The multivibrator is energized by a D.-C. voltage source E_{DC} which is connected through resistor R_P to terminals 21 and 23. Control windings C₁ and C₂ are interconnected in series opposing relationship to a polarity reversible signal voltage source E_S through variable resistor R_S.

In operation, the frequency, f_o, of the output voltage E_o will be determined by the saturable reactors SR₁ and SR₂.

Referring now to FIG. 2 of the drawings in which a graph is shown illustrating the relationship between the input control current, I_c, and the oscillation frequency, f_o, of the output voltage of the multivibrator of FIG. 1; the curve shows results of a test of the multivibrator of this invention in which the control current was applied in 0.5 milliamper steps ranging in value from -1.5 milliamperes to +1.5 milliamperes. Tape wound cores were used having an outside diameter of 1.5 inches and an inside diameter of 1% inches. The tape used has a thickness of 2 mils and a width of 1/8 inch.

Referring now to FIG. 3 of the drawings in which a differential type magnetic multivibrator is illustrated; a first multivibrator includes transistors Q₁', Q₂' and a second multivibrator includes transistors Q₁'' and Q₂''.

In the first multivibrator, the base of transistor Q₁' is connected to the collector terminal of transistor Q₂' through resistor R₁'. The base of transistor Q₂' is connected to the collector terminal of transistor Q₁' through resistor R₂'. The emitter terminals of transistors Q₁' and Q₂' are connected together at a common juncture 101. A first saturable reactor SR₁' includes saturable core 103, primary winding N₁', secondary or load winding N₃' and control winding C₁'. A second saturable reactor SR₂' includes saturable core 105, primary winding N₂', secondary or load winding N₄' and control winding C₂'. Primary windings N₁' and N₂' are connected in series aiding relationship to the collector terminals of transistors Q₁' and Q₂'. In the second multivibrator, the base of transistor Q₁'' is connected to the collector terminal of transistor Q₂'' through resistor R₁''. The base of transistor Q₂'' is connected to the collector terminal of transistor Q₁'' through resistor R₂''. The emitter terminals of transistors Q₁'' and Q₂'' are connected together at a common juncture 111. A third saturable reactor SR₁'' includes saturable core 113, primary winding N₁'', secondary or load winding N₃'' and control winding C₁''. A fourth saturable reactor SR₂'' includes saturable core 115, primary winding N₂'', a secondary or load winding N₄'' and

control winding C_2'' . Primary windings N_1'' and N_2'' are connected in series aiding relationship to the collector terminals of the transistors Q_1'' and Q_2'' . The two multivibrators may be energized by a common voltage source E_{DC} which is connected to junctures 121 and 123. The secondary windings N_3' , N_4' , N_3'' and N_4'' are connected in series aiding relationship to load 125. Control windings C_1' and C_2' are connected together in series opposing relationship. Control windings C_1'' and C_2'' are also connected together in series opposing relationship. The control circuit of the first multivibrator, including windings C_1' and C_2' is serially connected to the control circuit of the second multivibrator, including windings C_1'' and C_2'' , and to signal voltage source E_S through resistor R_c . In such a combined control circuit, the winding sense relationship of the windings may be considered in terms of magnetic flux directions. That is, for example, if a current flow I_c flowing through winding C_1' created a magnetic flux in core 103 in a clockwise direction, this same current flowing through windings C_2' and C_2'' would produce a counter-clockwise magnetic flux in cores 105 and 113, and the flow of this same current through winding C_2'' would produce a magnetic flux in a counter-clockwise direction in core 115.

With the differential or push-pull type of circuit arrangement of FIG. 3, the frequency of the first multivibrator comprising transistors Q_1' and Q_2' will be the same as the second multivibrator when there is no D.-C. signal applied to the control circuit, that is when $E_S=0$. When a signal is applied to the control circuit, the frequency of the first multivibrator f_0' will decrease and the frequency of the second multivibrator f_0'' will increase, for example. The frequency of the output voltage f_0 will then be the difference frequency, that is, $f_0=f_0''-f_0'$. As the signal is decreased or becomes negative the opposite is true, that is, the frequency of the first multivibrator will increase and the frequency of the second multivibrator will decrease.

Obviously, many modifications and variations of the present invention are possible in the light of the above teachings. It is therefore to be understood, that within the scope of the appended claims, the invention may be practiced otherwise than as specifically described.

What is claimed as new and desired to be secured by Letters Patent of the United States is:

1. A differential D.-C. to A.-C. converter having an A.-C. voltage output with a frequency proportional to the magnitude of a D.-C. signal voltage comprising,

a first switching transistor multivibrator having an output circuit,

a second switching transistor multivibrator having an output circuit,

a first saturable reactor having a first primary winding, a first load winding and a first control winding,

a second saturable reactor having a second primary winding, a second load winding and a second control winding,

a third saturable reactor having a third primary winding, a third load winding and a third control winding,

a fourth saturable reactor having a fourth primary winding, a fourth load winding and a fourth control winding,

means connecting said first and second primary windings to the output circuit of said first multivibrator in series aiding relationship,

means connecting the third and fourth primary windings to the output circuit of said second multivibrator in series aiding relationship,

means connecting said first and second load windings in series aiding relationship to form a first load circuit,

means connecting said third and fourth load windings in series aiding relationship to form a second load circuit,

45

50

55

60

70

75

means connecting said first and second control windings in series opposing relationship to form a first control circuit,

means connecting said third and fourth control windings in series opposing relationship to form a second control circuit,

a load,

a D.-C. signal voltage source,

means connecting said first and second load circuits to said load in series aiding relationship,

means connecting said first and second control circuits to said D.-C. signal voltage source in series opposing relationship.

2. A differential type D.-C. to A.-C. converter having an A.-C. output voltage with a frequency proportional to the magnitude of a D.-C. signal voltage comprising,

a first magnetic coupled multivibrator having an input circuit and an output circuit,

a second magnetic coupled multivibrator having an input circuit and an output circuit,

first saturable reactor means including saturable core means, a control circuit, a first load circuit and a second load circuit,

second saturable reactor means including saturable core means, a control circuit, a first load circuit and a second load circuit,

a D.-C. voltage source,

means connecting the input circuit of said first multivibrator to said D.-C. voltage source,

means connecting the input circuit of said second multivibrator to said D.-C. voltage source,

means connecting the first load circuit of the first saturable reactor means to the output circuit of said first multivibrator,

means connecting the first load circuit of said second saturable reactor means to the output circuit of said second multivibrator,

load means,

means connecting the second load circuit of said first saturable reactor means and the second load circuit of said second saturable reactor means to said load means in series aiding relationship,

a D.-C. signal voltage source,

means connecting the control circuit of said first saturable reactor means and the control circuit of said second saturable reactor means to said D.-C. signal voltage source in series opposing relationship.

3. A differential type D.-C. to A.-C. converter having a frequency proportional to the magnitude of a D.-C. signal voltage comprising

a first switching transistor multivibrator having an input circuit and an output circuit,

a second switching transistor multivibrator having an input circuit and an output circuit,

a D.-C. voltage source

means connecting said D.-C. voltage source to the input circuits of said first and second multivibrators,

a first saturable reactor system having a first primary circuit, a first control circuit and a first load circuit,

a second saturable reactor system having a second primary circuit, a second load circuit and a second control circuit,

means connecting said first primary circuit to the output of said multivibrator,

means connecting said second primary circuit to the output of said second multivibrator,

load means,

a polarity reversible D.-C. control signal source,

means connecting said first and second load circuits to said load means in series aiding relationship,
